(57) **CLAIM**

The ornamental design for a vehicle, toy replica and/or other replicas, as shown and described.

DESCRIPTION

FIG. 1 is a top left-side perspective view of a vehicle, toy replica and/or other replica according to said design, the top right-side perspective view being mirror symmetrical;
FIG. 2 is a left-side elevation view thereof;
FIG. 3 is a front elevation view thereof;
FIG. 4 is a right-side elevation view thereof; and,
FIG. 5 is a rear elevation view thereof.
The broken lines are for illustrative purposes only and form no part of the claimed design.
